[57] **CLAIM**

The ornamental design for a female anti-incontinence appliance, as shown and described.

DESCRIPTION

FIG. 1 is a side elevational view of a female anti-incontinence appliance, showing my new design, with all other sides being identical to that shown;

FIG. 2 is an end elevational view thereof; and,

FIG. 3 is an end elevational view thereof, opposite that shown in FIG. 2.

FIG. 1

FIG. 2

FIG. 3
